UNITED STATES PATENT OFFICE.

WILLIAM MCNAMES, OF ABERDEEN, SOUTH DAKOTA.

BURGLAR-ALARM SYSTEM.

Application filed November 6, 1924. Serial No. 748,228.

To all whom it may concern:

Be it known that I, WILLIAM MCNAMES, a citizen of the United States, residing at Aberdeen, in the county of Brown and State 5 of South Dakota, have invented certain new and useful Improvements in Burglar-Alarm Systems, of which the following is a specification.

This invention appertains to burglar 10 alarm systems and the primary object of the invention is to provide novel means for automatically sounding an alarm upon the opening of a door or window and for automatically discharging a gun at the intruder. 15 Another object of the invention is the provision of a spring actuated lever and a novel trip or catch for holding the lever in a set position against movement by the spring and means for releasing the catch 20 upon the operation of a door or window, the lever carrying means for actuating the gun when the release lever is released.

A further object of the invention is to 25 provide a novel mechanism for giving an alarm and for discharging a gun, when an intruder breaks into a house, the device being so constructed as to permit the alarm to be arranged at a point distant from the house, which is broken into, such as a police 30 station or the like.

A further object of the invention is to 35 provide a novel burglar alarm mechanism embodying a base plate to which is rigidly secured any preferred type of fire arm and a swinging operating lever, having resilient means connected thereto for normally urging the same in one direction for actuating the trigger of the said fire arm, the spring also forming means for actuating an operat- 40 ing rod for the alarm, novel means being provided and mounted upon said base for normally holding the lever against swinging movement under influence of the spring, and operable by the movement of door or 45 window.

A still further object of the invention is 50 to provide an improved burglar alarm of the above character, which will be durable and efficient in use, one that will be simple and easy to manufacture and one which can be placed upon the market at a small cost.

With these and other objects in view, the 55 invention consists in the novel construction, arrangement and formation of parts, as will be hereinafter more specifically described,

claimed and illustrated in the accompanying drawings, in which drawings,

Figure 1 is a side elevation of the improved device,

Figure 2 is a top plan view of the same, 60 parts of the alarm mechanism being shown in section, the view being taken substantially on the line 2-2 of Figure 1 looking in the direction of the arrows,

Figure 3 is a fragmentary side elevation 65 of the improved device looking in the opposite direction from Figure 1, parts of the device being broken away and in section,

Figure 4 is a transverse section through 70 the device taken on the line 4-4 of Figure 3 looking in the direction of the arrows illustrating the operating lever for actuating the trigger of the fire arm,

Figure 5 is a transverse vertical section 75 through the improved device taken on the line 5-5 of Figure 3 looking in the direction of the arrows illustrating the guide and latch for the operating lever.

Referring to the drawings in detail, 80 wherein similar reference characters designate corresponding parts throughout the several views the letter A generally indicates the improved device which embodies a conventional type of fire arm 10 and operating means 20 therefor and an alarm mechanism 40.

As stated the fire alarm 10 is of the conventional type and as shown is in the form of a rifle including a stock 11, a barrel 12, a hammer 13 and a trigger 14. This fire 90 arm 10 is arranged longitudinally of a supporting base plate 15 which can be formed of any desired material such as wood or the like. Adjacent to one end of the base plate 15 at one side of the longitudinal axis 95 thereof is secured a supporting bracket 16 to which is connected by means of bolts 17 the stock 11 of the rifle.

The operating means 20 for the rifle is 100 also utilized for setting in motion the alarm mechanism 40 which can be placed at a point distant from the fire arm, as will be hereinafter more fully described. The operating mechanism 20 embodies a relatively heavy swinging lever 21 which is pivoted at its lower end to a bracket 22 secured to the upper face of the base plate 15 at one side of the fire arm 10 and adjacent to the trigger 14 thereof. This lever has formed thereon or secured thereto a laterally ex- 110

tending trigger operating bar 23 and as the trigger 14 is arranged in the path of said bar, it is evident that when the lever 21 is forcibly swung toward the trigger that the gun will be discharged. This lever 21 has secured thereto a wire cable 24 which can be of any desired length and this cable is secured at its rear end to an actuating rod 25, which is slidably mounted within a guide opening formed in the supporting bracket 26. This operating rod 25 is also utilized for actuating the alarm mechanism 40 as will be hereinafter described. A contractile spring 27 is coiled about the rod 25 and has its opposite terminals secured to the bracket 26 and the rod 25 and this spring normally urges the rod 25 and the lever 21 in one direction for actuating the alarm and the rifle respectively.

20 In order to normally hold the lever 21 against swinging movement under the influence of the spring 27 I provide a latch for the said lever. This latch embodies an up-standing leaf spring 28 having a keeper lug 29 on its inner face under which is adapted to be positioned a rigid latch lever 30 carried by the said operating lever 21. This latch lever 30 is provided with a hook terminal 31 for engaging under the latch lug and the latch lug carries a guide 32 for directing the latch lever under the lug during the initial setting of the apparatus. This guide 32 is of a substantial U-shape in cross section, as can be seen by referring to Figure 5 of the drawing. The lower end of the guide 32 carries a depending loop 33 through which the latch arm or lever 30 is adapted to extend. The extreme upper end of the leaf spring 28 has secured thereto in any desired way an eye 34 to which can be attached any number of pull cables 35. These pull cables 35 are adapted to be attached to window sashes, doors and the like so that upon the opening thereof the leaf spring will be drawn back for moving the latch lug from out of engagement with the latch arm permitting the actuation of the operating lever and the operating rod. A guide eye 36 is provided for the pull cables and this guide eye can be supported by any desired type of bracket 36 which is secured to the base plate 15. The guide bracket 37 can also be utilized for holding the spring 28 in place and if desired the spring can be formed directly on the said bracket.

60 The alarm mechanism 40 also embodies a base plate 41 to which is secured a supporting bracket 42. This supporting bracket 42 has bolted or otherwise secured thereto any desired type of clock mechanism 43 for actuating a bell tapper 44 and a bell 45 is secured to the bracket in the path of the said tapper.

65 In order to normally prevent operation of the clock mechanism a pivoted dog 46 is car-

ried by the frame of the clock mechanism and this dog has its toothed end normally held in engagement with one of the clock wheels, by means of a contractile coil spring 47. The pivoted dog 46 opposite to the toothed end thereof is provided with a depending foot 48 which is disposed in the path of the operating rod 25 and it is obvious that when the operating lever 20 is released, that the rod 25 will strike the foot 48 lifting the toothed end of the dog and permitting operation of the clock mechanism and the sounding of the alarm.

70 The bracket 26 is carried by the base plate 41 as can be readily seen by referring to Figures 1 and 2 of the drawing.

75 Now the gun operating mechanism is adapted to be positioned directly in front of a door or window, while it is preferred that the alarm mechanism be placed at a point distant therefrom, such as in a police station or the like. It is therefore evident that the cable 24 can be of any desired length and can be trained over suitable guide pulleys or the like when necessary. It is also preferred to connect the pull cables 35 to the ring 34 in such a manner that the same can be readily disconnected from the release mechanism, when it is desired not to use the device.

80 From the foregoing description it can be seen that I have provided an improved mechanism which will be automatically set in operation upon the unauthorized opening of a door or window and which is so constructed as to both discharge a firearm and an alarm mechanism.

85 Arranged in the path of the lever 21 is a buffer 38 which is carried by a resilient standard 39. This limits the swinging movement of the lever under the influence of the contractile coil spring.

90 Changes as to details may be made providing the same do not depart from the spirit or scope of this invention, as defined by the claims.

95 What I claim as new is:—

100 1. In a device of the class described, a fire arm, including a barrel, a stop and a trigger an alarm mechanism including a bell, a pivoted lever for operating the trigger, a sliding rod for operating the alarm mechanism, means connecting the lever and rod together for synchronous movement, a single leaf spring for moving the rod and lever to an operating position, a rigid latch arm carried by the lever, a movable trip for engaging said arm for holding the lever and rod against movement, a guide carried by said trip for the latch arm, a pull cable for actuating the trip, and a guide for said pull cable.

105 2. In a device of the class described, a base plate, a fire arm rigidly secured to the base plate, an alarm mechanism including a bell,

a base plate for the alarm mechanism, a swinging lever for the fire arm carried by the first mentioned base plate, a sliding rod for actuating the alarm mechanism carried by the second mentioned base plate, means connecting the lever and the rod together for synchronous movement, a contractile spring coiled about the rod for normally urging the rod and lever to an operative position, a rigid latch arm carried by the lever having a hook terminal, an upstanding leaf spring secured to the first mentioned plate, a latch lug carried by said leaf spring for receiving said latch arm for normally holding the lever and rod against movement, a guide carried by the latch lug and spring for said latch arm, and an operating cable connected to the free end of said leaf spring.

3. In a device of the class described, a base plate, a fire arm arranged longitudinally of the base plate including a stack, a barrel, a hammer and a trigger, a bracket rigidly connecting the stack of a fire arm to the base plate, a lever pivotally secured to

the base plate at one side of the fire arm 25 adjacent to said trigger, a laterally extending trigger bar carried by the lever for operating the trigger of the fire arm, spring means normally urging the lever to an operative position, a buffer carried by the base 30 plate and disposed in the path of the lever for limiting the swinging movement thereof in one direction, an upstanding leaf spring carried by the base plate disposed forwardly of the lever, a latch lug carried by the leaf 35 spring, a rigid latch arm having a hook terminal carried by the lever adapted to engage under the latch lug, when the lever is in its set inoperative position, a U-shaped guide for the latch arm carried by the latch 40 lug, a pull cable secured to the free end of said spring.

In testimony whereof I affix my signature in the presence of two witnesses.

WILLIAM McNAMES.
